B. REICHARD.
HAT CREAMER RETAINER.
APPLICATION FILED FEB. 1, 1921.

1,406,078.

Patented Feb. 7, 1922.

Inventor:
Benjamin Reichard,
By his Attorney,
Geo. W. Mott,

UNITED STATES PATENT OFFICE.

BENJAMIN REICHARD, OF NEW YORK, N. Y.

HAT-CREASER RETAINER.

1,406,078.

Specification of Letters Patent. Patented Feb. 7, 1922.

Application filed February 1, 1921. Serial No. 441,564.

To all whom it may concern:

Be it known that I, BENJAMIN REICHARD, a citizen of the United States, and a resident of the borough and county of Bronx, 5 city and State of New York, have invented certain new and useful Improvements in Hat-Creaser Retainers, of which the following is a specification.

My improvements relate to the type of 10 soft hat crease-maintaining device set forth in my concurrent application Serial No. 310,775, filed July 14, 1919, and embodied in Letters Patent No. 1,367,205, issued to me Feb. 1st, 1921, and are designed to render 15 the same more effective and positive in function by counteracting any tendency thereof to slip out of place, or become loose upon or detached from, the inner portion of the crown of the hat to which the device is applied; the invention consisting essentially in 20 internally barbing the creaser, as described and claimed specifically, in such manner as to increase frictional contact with the sides of the hat crown bight and prevent displacement therefrom, substantially as hereinafter 25 set forth.

In the accompanying drawings,

Fig. 1, is an end elevation of the creaser;

Fig. 2, is an elevation of either side of 30 my improved hat creaser;

Fig. 3, is a cross section thereof taken upon plane of line 3—3, Fig. 2;

Fig. 4, is a similar sectional view of the 35 creaser as applied to a hat crown bight, the latter being also indicated in section;

Fig. 5, is a side elevation of my creaser, showing a modification in the barb arrangement;

Figs. 6 and 7, are elevations of opposite 40 sides of the creaser, illustrating another modification in the arrangement of the barbs;

Fig. 8, is a side elevation of the creaser, showing still another modification in barb 45 arrangement.

Fig. 9, is a like view showing still another modification in which a clearance aperture is formed in the side of the creaser adjacent to the barb points.

While I do not confine myself to the use 50 of any specific material in the construction of my device, my improved hat crease holder is preferably made of a single piece of relatively thin celluloid bent over upon itself 55 and permanently set; and consists of an essentially semi-cylindrical spine *s*, and side

members or jaws *j*, *j*, the longitudinal edges *e*, *e*, of which tend constantly to contact with each other, and hence to clamp any material inserted between them. In other 60 words, my crease retainer is preferably although not necessarily inherently elastic and resilient as heretofore,—the resilience of the spine *s*, particularly insuring the functioning of the clamping jaws *j*, *j*, and the novelty in the present case consisting in internally barbing one or both of the jaws *j*, *j*, so as to render more positive their contactual engagement with the portions of the hat crown interposed between them in the 65 formation of the crease (*k*).

Thus in Fig. 8, I indicate the formation of each jaw *j*, *j*, with an inturned and down-turned barb *b*; whereas Fig. 2, shows either or both jaws formed with a plurality of 70 such barbs, equidistantly positioned apart. Again, in Figs. 6 and 7, I illustrate the use of three barbs *b*, *b*, *b*, on one jaw, and two barbs *b*, *b*, on the other jaw, the barbs on the latter intervening or "breaking joints" 80 with those on the other side. In Fig. 5, I show the use of a plurality of connected barbs *b*, on either one or both jaws *j*, *j*, as may be preferred, or found most expedient. While in Fig. 9, I show a side of the creaser 85 formed with a clearance space *c*, for the points of the barbs *b*, *b*, to facilitate engagement thereof with the hat material. In fact I do not limit myself either to the number or the arrangement of the barbs formed on 90 my improved crease holder,—the essential feature of the invention being the supplementing of the jaws *j*, *j*, with internal barbing, single or plural, for the purpose designated; neither do I limit myself to the material used in the formation of the creaser, 95 since sheet metal, or an alloy may be used to advantage where cheapness of material and production is a commercial factor, since my inturned barbs *b*, *b*, render even non-resilient jaws *j*, *j*, effective for contactual engagement with the felt or other relatively soft penetrable, pliable material of which so called "soft" hats are formed.

By the term "barb" as herein used I mean 105 any upsetting and inturning of a portion or portions of the holder within the edges and confines thereof, the same being preferably formed medially, or approximately so, between the edges *e*, *e*, and the spine *s*, substantially as illustrated in the accompanying drawings; said barbing being inclined 110

inward and downward in the direction of the spine, which latter constitutes the bottom of the device in use, as will be understood by reference to Fig. 4. This inward and downward projection of the barbing increases frictional contact with the portions of the hat crown interposed between the jaws *j*, *j*, and counteracts any tendency to slip or looseness under the stress of handling and wear of the hat, the barbing *b*, supplementing the grip of the edges *e*, *e*, of the jaws or the hat crown, and positively resisting displacement unless the jaws are spread apart forcefully sufficiently to release the barbing. In other words, to pull or push the creaser downward without spreading the jaws apart, after application to the bight of the crown of the hat, would only tend to imbed the barbing more effectually in the material, and positively resist displacement under ordinary conditions of use.

While as before stated I do not confine myself to the use of any particular material, when elastic resilient material is employed for the purpose I prefer to make my hat creasing device of celluloid which is transparent, so that when in position on the inner side of the crown of the hat it is practically invisible except upon close inspection, because it harmonizes with the color of the material to which it is applied. Furthermore such material is relatively light in weight, while affording the qualities of strength and tenacity essential for the purpose.

The barbing *b*, may be die-stamped in the blank of which the crease retainer is formed,

in a manner well known in the art, or otherwise shaped and inturned, as may be found most expedient in manufacture.

By the term "internally barbed" as used herein I mean to designate inturned barbs *b*, *b*, formed entirely within the circumferential boundaries and edges of the side members or jaws *j*, *j*, with their apices extending in the direction of the hollow spine *s*, as clearly shown in the several figures of the accompanying drawings.

What I claim as my invention and desire to secure by Letters Patent is,

1. As an article of manufacture, a hat crease retainer of the character designated, comprising a one piece elastic resilient structure having a hollow spine and convergent clamping jaws having inturned barbs formed entirely within the circumferential edges of said jaws and with their apices extending toward said hollow spine, substantially in the manner and for the purpose set forth.

2. As an article of manufacture, a hat crease retainer of the character designated, comprising a transparent one piece elastic resilient structure having a hollow spine and convergent clamping jaws having inturned barbs formed entirely within the circumferential edges of said jaws and with their apices extending toward said hollow spine, substantially in the manner and for the purpose set forth.

BENJAMIN REICHARD.
